UNITED STATES PATENT OFFICE

ADAM WIDUCH, STANLEY HAYDUK, AND WALENTY SLIWA, OF MICHIGAN CITY,
INDIANA

AUTOMATIC RAILWAY GATE

Application filed May 9, 1929. Serial No. 361,630.

The present invention relates to automatic railway gates for railroad crossings and has for its main object the provision of a gate which is operable by means of the train approaching the crossing.

Another object of the present invention is the provision of a railway gate of the character indicated which may be simple in construction and efficient in its operation.

10 Another object of the present invention is the provision of an automatic railway gate for the use with railway crossings which may be operated by the train approaching the crossing from either direction with respect to 15 the crossing.

Another object of the present invention is the provision of an automatic railway crossing gate connected up with a suitable mechanism which may be actuated by bars positioned on each side of the crossing and lengthwise of the rails and which may be pressed by the wheels of the train, and for which bars suitable means may be provided whereby said bars may be kept in position and in abutment 25 with their cooperating rails.

With the above general objects in view and others that will appear as the nature of the invention is better understood, the same consists in the novel construction, combination 30 and arrangement of parts hereinafter more fully described, illustrated in the accompanying drawings and pointed out in the appended claims.

In the drawings forming a part of this application and in which like designating characters refer to corresponding parts throughout the several views,

Fig. 1 is a top plan view of the present invention showing the swinging members of 35 the gate in closed or operative position;

Fig. 2 is a side elevational view of the gate;

Fig. 3 is a side cross-sectional view of the gate lengthwise of the railway track or transversely of the crossing, the view having been 45 taken along line 3—3 of Fig. 1;

Fig. 4 is an end view of the gate partly in section and partly in elevation, the view having been taken transversely of the railway track along line 4—4 of Fig. 1;

50 Fig. 5 is a side elevational view of a bar,

with central portions thereof broken away, by means of which the mechanism of the gate is actuated;

Fig. 6 is a cross-sectional view through said bar and its cooperating rail, the view having been taken on line 6—6 of Fig. 5;

Fig. 7 is an elevational side view of a pulley constituting part of the present invention, showing the means for frictionally locking said pulley while the gate is in an open or 60 inoperative position;

Fig. 8 is a side elevational view of a swinging member; and

Fig. 9 is a top elevational view of said swinging member.

Referring to the drawings in detail there are shown therein conventional rails 10 positioned upon usual ties 11. Positioned below rails 10 and on a plane substantially with ties 11 is a box-like housing generally indicated by 12, which includes rectangular box frame 13 and platform 14 positioned upon said box frame 13 and in parallel relation with the ties, as plainly seen on Figs. 1 and 3. Adjacent the outer corners, and outside of the rails, platform 14 is provided with openings 15 for the purpose which will be hereinafter described.

Said platform 14 has openings made therein lengthwise of the rails, two of them outwardly of the rails, and one in between the rails, and for the purpose of covering the same, outer covers 16 and central cover 17 are provided and are longitudinally disposed in relation with rails 10 and in the path of 85 a road traversing the rails.

Positioned over each of said openings 15 are housings each of which includes a pair of upright parallel walls 18 which are in parallel relation with respect to the rails, and a U-shaped cover 19 which covers and fits over said parallel walls 18. For affixing said latter described housing to housing 12, or more specifically to platform 14, said walls 18 are secured or rigidly affixed thereto adjacent the edges of openings 15, by means of horizontal flanges 20 made at the lower edges of said covers 19, which flanges rest upon platform 14 and by means whereof said covers 19 are mounted thereupon.

Said housing, including walls 18 and U-shaped plates 19 for the purpose of simplicity are indicated on Fig. 1 by numeral 21 and will be referred to by that numeral in the remaining description.

Two shafts 22 which are in transverse relation with respect to the rails 10 are positioned within suitable slots or openings made in platform 14, the ends of each of said shafts 10 22 resting upon and within bearings 23, which are positioned upon cement blocks 24, as seen on Fig. 5, which cement blocks rest upon the ground and below platform 14, adjacent rails 10, but on the plane substantially 15 identical with the plane of ties 11, as clearly seen on Fig. 5. These shafts 22 are rotatably mounted upon said blocks 24 within bearings 23.

Rigidly mounted upon said shafts 22 and 20 adjacent the ends thereof, in line with openings 15 in the platform 14 are sprocket wheels 25. Rigidly mounted upon said shaft 22 and outwardly of said sprocket wheels 25 are pulleys 26, for the purpose which will be 25 hereinafter described.

Mounted in the upper ends of walls 18 in the housings 21 are shafts 27, each of which has rigidly mounted thereupon a smaller sprocket wheel 28, each of which is in alignment with the sprocket wheel 25 upon shaft 22. The outer ends of said shafts 27 project outwardly of said housings 21 and have rigidly mounted thereupon swinging members generally indicated by 29. Said larger 30 sprocket wheels 25 and smaller sprocket wheels 28 in each housing 21, are connected by sprocket chains 30, each of which, at two opposite points, and adjacent the central portion, is provided with a pair of turn buckles 35 35 31 for the purpose of tightening or loosening said sprocket chain in order that proper adjustment thereof upon the two sprocket wheels 25 and 28 may be attained.

For the purpose of actuating or revolving 40 shafts 22, a pair of bars 32 are provided for each rail and positioned alongside thereof and outwardly of the rail track. One of said bars 32 is provided for each shaft 22 as seen on Fig. 1, so that the position of said bars 32 45 with respect to each other and with respect of the crossing is on a diagonal line. The ends of each of said bars 32 disposed nearer to the crossing are curved and downwardly 50 extending as at 33, while the other, outward end of each of said bars 32 is tapered for facilitating the engagement of the bar with the wheels of an approaching train. Each of said bars 32 is comparatively long and is 55 adapted to remain in close abutment with the outer face of each rail, and in order to eliminate any possible deflection or bending of each of said bars from its cooperating rail when 60 under pressure of the train wheels, suitable 65 supports are provided to maintain said bars

in close contact with the rails as will be presently described.

Each of said supports includes base 34 which is adapted to be positioned and rigidly mounted upon ties 11 and adjacent the outer edges of the base of the rail, as seen on Fig. 6. Rigidly formed with and upwardly projecting from said base 34 is plate 35, which, when the support is in its operative position, remains longitudinally with respect to ties 11 or transversely of rail 10. Rigidly formed with said base 34 as well as with one face of plate 35, and at the edge of said base 34 nearer to the rail 10 are two spaced lugs 36 which are adapted to receive therebetween the lower end of link 37 wherein said lower end thereof is pivotally mounted upon pin 38.

The upper end of said link 37 is pivoted at the outer face of bar 32 upon pin 39.

In the operative position of the support hereinabove described with respect to rail 10 and bar 32 the edges of plate 35 will contact with the outer face of bar 32, the latter remaining between the head of the rail 10 and said abutting edge of plate 35, while the face of link 37 which abuts with bar 32 will remain in alignment with the face of plate 35 which abuts said bar 32. This operative co-operation between the several parts of said support and bar 32 necessitates the off-setting of one of the lugs 36 towards rail 10 so that the same may remain below bar 32 as seen on Fig. 6.

There are a number of the supports hereinabove described, one positioned upon each tie throughout the length of bar 32.

Said curved ends 33 of bars 32 are disposed above shafts 22 and are received within the bifurcated ends of lever arms 40 wherein they are pivoted upon pins 41, said arms being rigidly mounted upon said shafts 22 so that when there is pressure exerted upon bars 32 by the train wheels a rotary movement may be imparted to shafts 22 when said bar 32 and arm 40 assume the position shown by dotted lines on Fig. 5.

Two pulleys 26 on one side of the railroad track are connected by means of cable 42 one end of which is secured to one pulley 26 as at 43 and remains at a point which is lowermost when the swinging members 29 are in an operative or closed position as plainly seen on Fig. 3. The other end of said cable 42 is secured to the opposite pulley 26 on the same side of the track and remains at the uppermost point upon said last named pulley as at 44 when the gates are closed. A similar cable 45 connects the two pulleys 26 on the opposite side of the track, but in this instance the end of said last named cable is secured at the lowermost point of that pulley 26 which remains on the right side of the crossing, reference being had to Fig. 1, when the gates are closed. The other end of said cable 45 is secured to the opposite pulley 26 on the same 125 130

side of the track at such point of said last named pulley which is uppermost during the position of said pulley when the gates are closed. Said cables 42 and 45 are adapted to 5 operate simultaneously regardless from which direction the train approaches.

Assuming that the train approaches from the direction indicated by the arrow on Fig. 1, the wheels of the train will exert pressure 10 on bar 32 at the right side of the crossing which will bring about a downward swinging movement of lever arm 40 due to the pressure exerted thereupon by the curved end 33 of bar 32. This will cause the rotation of 15 shaft 22 in the direction away from the approaching train. Since sprocket wheels 25 are rigidly connected with said shaft 22, the rotary movement of said shaft imparted thereto by bar 32 will also be imparted to said 20 sprocket wheels 25 on the same side of the crossing, and the rotation of said sprocket wheels 25 will be imparted, by means of sprocket chain 30, to the upper smaller sprocket wheels 28, which likewise will 25 rotate to the direction of rotation of shaft 22 and sprocket wheels 25. Shafts 27 on the same side of the crossing will rotate with said smaller sprocket wheels 28, by means of which 30 operation the swinging members 29 will be brought down from the open upright position to the horizontal closed position shown on Fig. 3.

Simultaneously with the above operation cable 45 will be wound upon pulley 26 which 35 remains adjacent bar 32 now under discussion, or in other words said cable 45 will be pulled toward or in the direction of said last named bar 32, which operation will cause the rotation of pulley 26 to which the opposite end of cable 45 is attached, and since 40 said end of cable 45 is attached to the opposite pulley 26 now in question, at a point which is diametrically opposite from the pulley adjacent said bar 32, the rotation of said 45 pulley to which said other end of said cable 45 is attached, is the reverse of that to which pulley 26 adjacent bar 32 is rotated. This 50 operation will cause the rotation of shaft 22 on the left side of the crossing in the reverse direction from the direction of the first mentioned shaft 22, that is in the direction toward the approaching train or to the direction reverse from that indicated by arrow on Fig. 1. The rotation of said shaft 22 55 on the left side of the crossing will also impart rotary movement to pulley 26 on the opposite side of the railroad track and this operation will cause the rotation of smaller sprocket wheels 28 on said left side of the crossing in the same direction through the medium of sprocket chains 30. This operation will cause rotation of shafts 27 in the direction of rotation of said smaller sprocket wheels 28, in consequence of which the swinging members 29 on the left side of the cross- 60

ing will be brought to operative or closed position illustrated on Figs. 1 and 3.

Assuming that the swinging members 29 are open or in an upright position and the train approaches the crossing from the opposite direction from that indicated by arrow on Fig. 1, the train wheels will press upon bar 32 on the left side of the crossing, reference being made to Fig. 1, which will cause the rotation of shaft 22 away from the direction of the approaching train through the medium of lever arm 40, as already described. This operation will cause the rotation of pulleys 26 on the left side of the crossing in the direction of the rotation of shaft 22 on the same side of the crossing and swinging members 29 on the same side of the crossing will be brought to closed or horizontal position by virtue of rotation of sprocket wheels 28 on the same side of the crossing due to the shifting of the sprocket chains 30. Simultaneously with this operation cable 42 is wound upon respective pulley 26, normally, when the gates are in an open upright position the end of said cable 42 remaining substantially on the plane with platform 14, in consequence of which operation said cable will be pulled in the direction of the approaching train from the left side of the crossing, and the other end of said cable, which normally also remains substantially on the plane with platform 14, will cause the rotation of the opposite pulley 26 on the same side of the railroad track in the reverse direction from that of pulley to which end 43 of cable 42 is attached. In consequence of the rotation of pulleys 26 through which end 44 of cable 42 is attached, the respective shaft 22 will also rotate with said pulley and will cause the rotation of the opposite pulley 26 on the other side of the railroad track, and the two pulleys, through the medium of larger sprocket wheels 25, will cause the rotation of their respective smaller sprocket wheels 28 in the same direction 100 through the medium of sprocket chains 30, whereby swinging members 29 on the right side of the track will be brought to horizontal or closed position. 105

Each of said cables 42 and 45 is provided with turn buckles 46 whereby the same may be tightened or loosened as the operativeness of said cables may from time to time require. 115

For each of said cables 42 and 45, roller 47, adjacent one of the housings 21, is provided for guiding the movement of said cables. 120

Each of said swinging members 29 at its outer end is provided with weight 48 for the purpose of bringing said swinging member to the open inoperative position illustrated by full lines on Fig. 2. Said weight 48 should be rather heavy in order that the same may bring about the reversal of the rotation of the several shafts, pulleys and sprocket 125 chains 30. 130

wheels after the train has passed the crossing and released the pressure upon bars 32. Of course, when the train has left said bars, the same will assume their normal inoperative position shown by full lines on Fig. 5, and it is to be understood that said bars 32 in their inoperative positions remain with their upper edges raised or above the heads of rails 10.

Each of said swinging members 29 is made of two sections which are connected by hinges 49, and the opposite faces of the hinged ends are connected by coil springs 50. This arrangement is made so that if a vehicle should by accident be found between the several 15 swinging members and upon the railroad track, the same may escape by driving against said swinging members which would open on a horizontal plane upon said hinges 49, and thereafter the same would automatically 20 close due to the tension of said coil springs 50.

One of said pulleys 26 is provided on its periphery with a projection 51, which, when the swinging members 29 are in open vertical position, remains at the lowermost point of 25 said pulley 26. Below said pulley, and suitably mounted is frame 52 which receives therewithin block 53 which is adapted to make upright cushioning movement by virtue of coil springs 54 positioned therebelow. The 30 upper face of said block 53 has a depression corresponding to the outline of said projection 51, so that when said pulley assumes the position illustrated on Fig. 7, said projection 51 remains within said depression in block 35 53. This arrangement permits frictional locking of one of said pulleys 26, which in consequence prevents movement of the mechanism of the entire gate which otherwise would be caused by the pressure of the wind 40 at the opened swinging members 29 or other causes.

While there is described herein a preferred embodiment of the present invention, it is nevertheless to be understood that minor 45 changes may be made therein, without departing from the spirit and scope of the invention as claimed.

What we claim as new is:

1. In an automatic railway crossing gate 50 comprising swinging members, shafts disposed below the rails, means between said shafts and said swinging members for transmitting the rotation of said shafts to said swinging members for the purpose of bringing 55 said swinging members from an upright open position to a horizontal closed position, bars associated with the rails, the ends of said bars adjacent the crossing being bent towards said shafts, said bars being adapted 60 for actuation by the wheels of the train, lever arms rigidly connected by their one ends to said shafts, the other ends of said lever arms being in pivotal connection with said bent ends of said bars, and means upon the ties for 65 laterally supporting said bars for maintain-

ing the same in an operative association with the rails.

2. In an automatic railway crossing gate 70 including swinging members, a bar positioned along side of the rails, said bar being adapted for actuation by the train wheels for bringing said swinging members to horizontal closed position, base plates positioned upon the ties and abutting the rail bases, an upwardly projecting plate integrally formed with said base plate, said upwardly projecting plate being in transverse relation with the rail, the edge of said last named plate in conjunction with the head of the rail forming a recess for receiving therewithin 75 said bar, a pair of spaced lugs integrally formed with said base plate and said upwardly projecting plate, and a link pivotally positioned by one of its ends between said lugs and by its upper end pivotally connected to said bar, the inner face of said link being in alinement with the edge of said upwardly projecting plate which is nearest to the rail.

3. In an automatic railway crossing gate 80 including swinging members, a bar positioned along side of the rails, said bar being adapted for actuation by the train wheels for bringing said swinging members to horizontal closed position, base plates positioned upon the ties and abutting the rail bases, an upwardly projecting plate integrally formed with said base plate, said upwardly projecting plate being in transverse relation with the rail, the edge of said last named plate in conjunction with the head of the rail forming a recess for receiving therewithin 85 said bar, a pair of spaced lugs integrally formed with said base plate and said upwardly projecting plate, and a link pivotally positioned by one of its ends between said lugs and by its upper end pivotally connected to said bar.

4. In an automatic railway crossing gate 90 including swinging members, a bar positioned along side of the rails, said bar being adapted for actuation by the train wheels for bringing said swinging members to horizontal closed position, base plates positioned upon the ties and abutting the rail bases, an upwardly projecting plate integrally formed with said base plate, said upwardly projecting plate being in transverse relation with the rail, the edge of said last named plate in conjunction with the head of the rail forming a recess for receiving therewithin 95 said bar, a pair of spaced lugs integrally formed with said base plate and said upwardly projecting plate, and a link pivotally positioned by one of its ends between said lugs and by its upper end pivotally connected to said bar, one of said lugs being beyond the edges of said two plates which are nearer to the rail.

5. In an automatic railway crossing gate 100

including swinging members, bar positioned along side of the rails, said bar being adapted for actuation by the train wheels for bringing said swinging members to horizontal
5 closed position, base plates positioned upon the ties and abutting the rail base, an upwardly projecting plate integrally formed with said base plate, said upwardly projecting plate being in transverse relation with
10 the rail, the edge of said last named plate in conjunction with the head of the rail forming a recess for receiving therewithin said bar, a pair of spaced lugs integrally formed with said base plate and said upwardly projecting plate, said lugs being in longitudinal relation with the rail, the outer face of the lug which is nearest to the rail being in alinement with the outer face of said bar, and a link pivotally positioned by
15 20 one of its ends between said lugs and by its upper end pivotally connected to said bar.

In testimony whereof, we affix our signatures.

ADAM WIDUCH.
STANLEY HAYDUK.
WALENTY SLIWA.
